UNITED STATES PATENT OFFICE.

GEORGE E. ROBERTS, OF SCHENECTADY, NEW YORK.

AUTOMATIC WRENCH.

1,391,581.

Specification of Letters Patent. Patented Sept. 20, 1921.

Application filed March 1, 1921. Serial No. 448,789.

To all whom it may concern:

Be it known that I, GEORGE E. ROBERTS, a citizen of the United States, residing at Schenectady, in the county of Schenectady, 5 and State of New York, have invented certain new and useful Improvements in Automatic Wrenches; and I do hereby declare the following to be a full, clear, and exact description of the invention, such as will 10 enable others skilled in the art to which it appertains to make and use the same.

This invention relates to new and useful improvements in automatic wrenches and has for its primary object the provision of 15 a self-setting movable jaw adapted to adjust itself to a nut or bolt when released from a locked position, obviating the necessity of removing the wrench from the nut or bolt to obtain a fresh grip thereon 20 and also dispensing with the slow finger adjustment now employed on wrenches of similar character.

Another object of this invention is the provision of a locking element for holding 25 the movable jaw in its various positions and which is provided with means for permanently locking the movable jaw against adjustment when desired and also capable of allowing an actuating means to operate 30 the same to free the movable jaw and permit the latter to automatically move toward the stationary jaw.

A further object of this invention is the provision of an automatic wrench of the 35 above stated character which will be simple, durable and efficient, and which may be manufactured and sold at a comparatively low cost.

With these and other objects in view as 40 will become more apparent as the description proceeds, the invention consists in certain novel features of construction, combination, and arrangement of parts as will be hereinafter more fully described and 45 claimed.

For a complete understanding of my invention, reference is to be had to the following description and accompanying drawings, in which:

Figure 1 is a side elevation, illustrating

an automatic wrench constructed in accordance with my invention,

Fig. 2 is a vertical sectional view illustrating the same,

Fig. 3 is a transverse sectional view taken 55 on the line 3—3 of Fig. 1,

Fig. 4 is a similar view taken on the line 4—4 of Fig. 1,

Fig. 5 is a similar view taken on the line 60 5—5 of Fig. 1.

Referring in detail to the drawings, the numeral 1 indicates a shank that has formed integrally with one end a stationary jaw 2 having an inclined active face 3. The other end of the shank 1 is reduced as illustrated 65 at 4 and has mounted thereon grips 5 that are engaged by a ferrule 6 and the latter is secured to the reduced end 4 of the shank by a rivet 7. A movable jaw 8 is associated with the stationary jaw 2 and is provided 70 with an inclined active face 9 co-operating with the inclined active face 3 of the jaw 2 in gripping nuts, bolts, and the like, and the movable jaw 8 is formed integrally with a body 10 that is slidably mounted on the 75 shank 1. The shank 1 is provided with a series of teeth 11 along its lower edge adapted to be engaged by teeth 12 formed on a locking block or element 13 and the latter is slidably mounted within a recess 14 80 formed within the body 10. The locking element 13 is normally urged in the direction of the shank 1 by means of a leaf spring 15. The leaf spring 15 is connected to an 85 adjusting pin 16 carried by the body whereby its tension on the locking element may be increased and decreased as desired, and when increased the locking element is permanently held in engagement with the shank 1 so that the teeth thereof interlock with the teeth 11 90 and prevent the movable jaw 8 from having relative movement in respect to the stationary jaw 2. The locking pin may be adjusted 95 so as to decrease the tension on the spring 15 and when so adjusted the locking block or element 13 may be moved away from the shank thus disengaging the teeth 11 and 12 through the medium of an actuating lever 17. The lever 17 is confined within a slot 18 formed in the shank 1 and is pivotally 100

mounted as illustrated at 18 so that on movement of the lever in one direction, it will engage the locking element 13 and disengage the teeth thereof from the teeth 11 consequently freeing the jaw 8 and permitting the same to have relative movement in respect to the stationary jaw. The lever 17 is so pivoted as to provide said lever with a comparatively long end and a comparatively short end and the short end has pivotally connected thereto a push pin or button 19 operable within a recess 20 formed in the handle of the wrench. A coil spring 21 is located within the slot or groove of the shank 1 and bears against one wall thereof and the short end of the lever for the purpose of moving the long end of the lever away from the locking element 13.

A pressure placed upon the push pin or button 19 rocks the lever 17 on its pivot 18 disengaging the locking element 13 from the shank and the movable jaw 8 is then urged in the direction of the stationary jaw by means of an expansion spring 22, thus it will be seen that the movable jaw 8 is quick and self-setting when released from a locked position and obviates the necessity of removing the wrench from a nut or bolt when desiring to obtain a fresh grip on the latter.

One end of the spring 22 bears against the body 10 while the other end bears against one end of the handle. A casing 24 incloses the spring 22 and receives one end of the handle and its other end receives the body 10 so that said body may slide into and out of the casing during the use of the wrench or the adjustment of the movable jaw. The casing 24 is provided with a slot disposed in alinement with the locking pin 16 so as to receive the latter when the movable jaw is moved in the direction of the handle.

While I have shown and described the preferred embodiment of my invention, it will be understood that minor changes in construction, combination, and arrangement of parts may be made without departing from the spirit and scope of the invention as claimed.

Having thus described my invention what I claim is:

1. A wrench comprising a shank having a groove, a handle carried by said shank, stationary and movable jaws carried by said shank, means for urging the movable jaw toward the stationary jaw, a locking element carried by the movable jaw and engaging said shank, and an actuating means mounted within the groove of the shank and adapted to be operated to disengage the locking element from the shank.

2. A wrench comprising a shank having a groove, stationary and movable jaws carried by said shank, means for normally urging the movable jaw toward the stationary

jaw, teeth formed on said shank, a locking element slidably mounted on the movable jaw, teeth formed on said locking element, tension means normally urging the locking element toward the shank, and an actuating means mounted in said groove and adapted to be actuated to move the locking element against its tension means for disengaging the teeth thereof from the teeth of the shank.

3. A wrench comprising a shank having a groove, stationary and movable jaws carried by said shank, means for normally urging the movable jaw toward the stationary jaw, a spring pressed locking element carried by the movable jaw and adapted to engage the shank, an adjusting means for the locking element, an actuating lever pivoted in said groove, and an operating means connected to said actuating lever for moving the same into engagement with the locking element to free the same from the shank.

4. A wrench comprising a shank having a groove, stationary and movable jaws carried by said shank, a handle for said shank, means for normally urging the movable jaw toward the stationary jaw, a locking element slidably supported by the movable jaw, tension means for urging the locking element into engagement with the shank, means for varying the tension of said tension means, a lever pivoted in said groove, tension means engaging said lever for holding the same away from the locking element, and a push button connected to the lever and extending through the handle for moving the lever into engagement with the locking element to disengage the latter from the shank.

5. A wrench comprising a shank having a groove, stationary and movable jaws carried by said shank, a handle for said shank, tension means between said handle and the movable jaw, a locking element carried by the movable jaw, tension means urging the locking element into engagement with the shank, a casing slidably receiving the removable jaw and engaging the handle and inclosing the first named tension means, a locking lever pivoted in said groove and having a short end and a long end and the last named end disposed over the locking element, tension means engaging the short end of the lever, and a button connected to the short end of the lever and extending through the handle for rocking said handle on its pivot to engage the locking element and disengage the latter from the shank.

6. A wrench comprising a shank having a groove, a stationary jaw formed on said shank, a handle carried by said shank, a body slideable on said shank, a movable jaw formed on said body, a locking element slidably mounted in said body and adapted to

engage the shank, tension means for said locking element, tension means interposed between the handle and the body, an actuating lever pivoted in said groove, tension means engaging said lever and a push pin connected to the lever and extending through the handle and adapted to move the lever into engagement with the locking ele-

ment to disengage the latter from the shank when pressure is placed thereon.

In testimony whereof I affix my signature in presence of two witnesses.
